SHEWARD & STANBERY.

Car Brake.

No. 64,040.

Patented Apr. 23, 1867.

United States Patent Office.

JAMES SHEWARD AND GEORGE A. STANBERRY, OF DUNKIRK, NEW YORK.

Letters Patent No. 64,040, dated April 23, 1867.

IMPROVEMENT IN CAR-BRAKES.

The Schedule referred to in these Letters Patent and making part of the same.

TO ALL WHOM IT MAY CONCERN:

Be it known that we, JAMES SHEWARD and GEORGE A. STANBERRY, of the town of Dunkirk, county of Chautauqua, State of New York, have invented a new and improved Method of Applying Brakes to the Wheels of Railroad Cars and other vehicles, for the purposes of regulating their motion and of placing in the hands of the engineer, conductor, or other single person, the power to apply the brakes on a train of cars by one motion and from any given part of the train, and while the same is in motion; and we do hereby declare that the following is a full and exact description thereof, reference being had to the accompanying drawings, and to the letters of reference marked thereon.

The nature of our invention consists in using a worm or endless screw upon the axle, and from this, by means of a cog-wheel working into it, secure a slow motion under high speed; and from the motion of the cog-wheel, by means of a face-plate and friction, secure the winding up upon a shaft the chain attached to the lever of the brakes. The principal use designed for our invention is setting brakes on railroad cars.

To enable others to make and use our invention, we will describe its construction and operation, as applied to railroad passenger cars, with the assistance of the accompanying drawings.

Let Figure 1 represent part of a "truck" of a car, showing a wheel, part of the timbers, part of the axle, and our invention as applied in perspective.

Figure 2 represents a sectional view of the various parts of our invention; and

Figure 3 shows a sectional view of the worm or screw and the axle.

The letters of reference are the same in each figure.

A and B are cast-iron bars, through which pass the wrought-iron rods C C. The wrought-iron rods C C are about one and a half or one and three-eighths inch diameter, with a head on the lower end, at e e, and a screw cut down nearly half their length, as shown in the drawings. These rods pass through a plank, R, of about two inches thickness, twelve inches width, and long enough to reach over and be securely bolted on the safety timber of the truck S. The nuts d d d d d d d are used for the purpose of adjusting the cross-bars A and B and for sustaining the frame on the plank R at the point needed to place the cog-wheel K in line with the centre of the axle U. E is a wrought-iron shaft of one and a half inch diameter, upon which is firmly fastened a face-plate, I. This shaft passes through the cog-wheel K and into the cross-bar B, as shown in fig. 2, and also through the plank R. Upon its upper end is a lever or pulley marked F. Resting upon the upper end of the shaft E is a bolt, H, of hardened steel, and having a shoulder upon which the lever G rests. This bolt passes through and is steadied by the cross-bar A. Upon the lower face of the cross-bar A there are two inclined planes marked y. Fitting upon these planes are two similar reversed ones on the lever G, the object of which is, upon moving the lever, to force the bolt H down upon the shaft E. In the cross-bar B is a chamber, in which is placed a spring, L, of India rubber, or other material, with disks or plates, m m, above and below it, and the object of which spring is to keep the face-plate I apart from the cog-wheel K. The necessary strength of this spring is secured by the temper screw o. K represents a cog-wheel working loosely upon the shaft E and into the worm or screw, as shown in fig. 1. This wheel is represented as about eighteen inches diameter, and must be cast, with its cogs chilled, of iron. Upon the upper side of K is a face or disk marked 7, and upon which the face of the plate I fits. When the invention is not in use for setting the brakes the spring L keeps the face-plate I about one-eighth or one-sixteenth of an inch from the face of the cog-wheel K, as shown in the drawings at 7. Between the cross-bar A and the nuts d d, in the upper end of the rods C C, are India-rubber springs, n n, for the purpose of regulating the pressure of the bolt H upon the shaft E and compensating for any irregularity that may exist in the faces of the plate and wheel at 7. Fig. 3 is designed to show how the worm or screw is attached to axles already in use. (We propose to have the worm or screw manufactured of wrought iron upon new axles and forming a part thereof.) Upon the axle U two sections of the worm or screw, shown at T, are fastened by lugs and bolts, as at x x x x. The inner concavities of these sections have a diameter larger than that of the axle, and after being bolted together around the axle, and adjusted so as to revolve truly, the intervening space is filled with lead, tin, or other soft metal, by casting, as shown at v v v v, fig. 3, after which the bolts are still further tightened and the screw is ready for use. To insure accuracy and tightness in the adjustment of the worm or screw, we insert a slip of sheet iron between the joints until after

the soft metal is cast into the space intervening between the axle and the pieces of the worm, after which we withdraw the sheet-iron strips and tighten the bolts.

Having constructed the frame of cross-bars A and B with the rods C C, having the shaft E, bolt H, lever G, and cog-wheel K in their places, as shown in fig. 1, the plank R is bolted into the safety timbers of the truck so as to throw the cogs of K into the meshes of the screw or worm with the centre of the face of K on a line with the centre of the axle U. When the car moves the wheel K revolves around the shaft E with regular motion and slowly, producing no effect upon the shaft or face-plate I. Now pull the lever G, as shown in fig. 1, toward you. The inclined planes y immediately force the shaft E with the face-plate I down upon the face or disk of the wheel K until the two faces come together with a force equivalent to that applied upon the lever G. As soon as these faces are forced together the face-plate I, being fast upon the shaft E, turns with the cog-wheel, carrying the shaft and the lever or pulley F. The chain of the brake-lever, being attached to F, as shown at P, fig. 2, is wound up or tightened until the pull upon it counterbalances the amount of friction created between the faces of the plate I and wheel K, after which the wheel K will continue to revolve, merely holding the face-plate I to the point of pull or tension already obtained. More power being then applied to the lever G, a further winding of the chain takes place, until at length the brakes are "set" enough to stop the revolution of the car-wheels, when all further strain is impossible. This arrangement we claim will enable the brakeman to put any desired amount of "set" upon his brakes at will. In order to enable an engineer on his locomotive to control all the brakes upon his train, we propose to connect the end of the lever G, at Z, with a cord running through the train to the cab of the locomotive, and so arranged as that a pull upon any part of the cord will, in any part of the train, pull upon the lever G of each of the cars and thus force the faces of the plate I and wheel K together with a power of winding up the brake-chain proportioned to the pull on the cord.

We do not claim as our invention any arrangement of the cord for operating upon the lever G; we do not claim to have invented the worm or endless screw, or the manner of putting the same on; we do not claim to have invented the use of friction for the purpose of setting brakes, as these are devices or uses well known.

What we do claim as our invention, and desire to secure by Letters Patent, is—

The application of the worm or endless screw to the axle of any vehicle, where the axle revolves in combination with a cog-wheel, to produce a slow motion under a high speed, and a face-plate forced upon the face of the cog-wheel as described herein for the purposes set forth.

JAMES SHEWARD,
GEO. A. STANBERY.
